OR D 20,100

DESIGN.

—
W. W. NOBLE.
STOVE PLATE.

No. 20,100.

Patented Aug. 12, 1890.

UNITED STATES PATENT OFFICE.

WILLIAM W. NOBLE, OF PHILADELPHIA, PENNSYLVANIA.

DESIGN FOR A STOVE-PLATE.

SPECIFICATION forming part of Design No. 20,100, dated August 12, 1890.

Application filed July 21, 1890. Serial No. 359,444. Term of patent 7 years.

To all whom it may concern:

Be it known that I, WILLIAM W. NOBLE, a citizen of the United States, and a resident of Philadelphia, Pennsylvania, have invented 5 a new and original Design for a Stove-Plate, of which the following is a specification.

My design for a panel of a stove is fully shown in the annexed photographic representation.

- 10 The leading feature of the design is the representation of a mounted knight and the representation of a cluster of emblems. On the raised surface of the door A is the representation of a knight in armor mounted on an armored horse, the knight having at his side a shield and having in one hand a spear. On 15 the door is an emblem consisting of the representation of a cluster of emblems—such as shields, flags, &c. This design is also carried out on the door B. In this case it is used 20 as a center-piece.

The design set forth can be placed on other plates of a stove without departing from my invention.

I claim—

- 25 1. The design for a stove-plate, as herein shown and described.
- 2. In a design for a stove-plate, the design for a door having a representation of a mounted knight in armor thereon, as herein 30 shown and described.
- 3. In a design for a stove-plate, the design for a medallion consisting of the cluster of emblems, as herein shown and described.

In testimony whereof I have signed my 35 name to this specification in the presence of two subscribing witnesses.

WILLIAM W. NOBLE.
